(57) **CLAIM**

The ornamental design for an organizer with drawers, as
shown and described.

DESCRIPTION

FIG. 1 is a top, front, right-side perspective view of an
organizer with drawers showing my new design;
FIG. 2 is a front elevational view thereof;
FIG. 3 is a left-side elevational view, the right side eleva-
tional view being a mirror image thereof;
FIG. 4 is a rear elevational view thereof;
FIG. 5 is a top plan view, the bottom plan view being a
mirror image thereof; and,
FIG. 6 is a top, rear, right-side perspective view thereof.
